UNITED STATES PATENT OFFICE.

WILLARD F. RICHARDS, OF DEPEW, NEW YORK, ASSIGNOR TO GOULD COUPLER COMPANY, OF NEW YORK, N. Y.

CAR-COUPLING.

1,164,666.

Specification of Letters Patent. Patented Dec. 21, 1915.

Application filed September 8, 1913. Serial No. 788,499.

To all whom it may concern:

Be it known that I, WILLARD F. RICHARDS, a citizen of the United States, residing at Depew, in the county of Erie and State of New York, have invented a new and useful Improvement in Car-Couplings, of which the following is a specification.

This invention relates more particularly to improvements in lock operating mechanisms for car couplers of the kind shown, for example, in my pending application for patent, No. 725,575, filed Oct. 14, 1912, in which the vertically movable knuckle lock can be operated from the bottom of the coupler. The operating device is, however, not limited in its use to couplers of this kind.

The object of this invention is to provide a simple and practical lock operating mechanism for car couplers which is adapted for use in connection with an actuating lever of the kind that is arranged transversely of the car to swing in a vertical plane parallel with the end of the car; and also to construct the mechanism so that it can be readily placed in operative connection with the actuating lever on the car, and so that the mechanism will operate freely and will not be strained or caused to bind by reason of the movements of the coupler on the car.

In the accompanying drawings: Figures 1 and 2 are fragmentary front elevations, partly in section, of a car having a coupler operating mechanism embodying the invention and showing the parts of the mechanism in different positions. Fig. 3 is a transverse sectional elevation thereof on line 3—3, Fig. 1.

A represents a car coupler, and b the buffer beam or end sill of a car to which the coupler is applied. The coupler shown has the usual horizontally swinging knuckle a and a knuckle lock a' which is slidable vertically in the coupler head into and out of engagement with the tail of the knuckle, and which, in its lower position shown in Fig. 1, locks the knuckle and, in its upper position shown in Fig. 2, releases the knuckle.

C represents a lock lifting rod or link which extends up through an opening in the floor of the coupler head and is connected at its upper end to the lock, preferably by a knob or rounded portion c at the upper end of the lifting rod loosely fitting in a correspondingly shaped socket c' in the lock.

These parts of the coupler are similar to the corresponding parts of the coupler and are more fully described in my above mentioned co-pending application. The coupler could, however, be of other construction having a lock adapted to be lifted by a rod or link, such as shown, extending upwardly into the coupler head.

The lower end of the lifting rod or link C is pivotally secured to a lever D, which is pivoted on the lower portion of the coupler head so as to swing in a vertical plane transversely of the coupler. This lever is preferably pivoted by a pin d to ears d' on one side of the coupler head. The lifting rod is thus guided in its movement into and out of the coupler head by the knuckle lock and the lever D, both the rod or pin and the lever moving in a vertical plane extending transversely of the coupler.

E represents the actuating lever of the lock operating mechanism. This lever, as usual, extends transversely of the car and is fulcrumed in a bracket e secured to the car, so as to swing in vertically. In the construction shown this lever consists of two parts e' and e'', the part e' being pivoted intermediate of its ends in the bracket e and having a part extending toward the side of the car, and the part e'' of the lever being also pivoted in the bracket e and extending toward the coupler head. The two parts of the lever are connected by a projecting portion e³ formed on the inner end of the part e' and embracing the lower face of the part e'', so that when the outer end of the part e' of the lever is depressed, it will raise the part e'' of the lever and cause it to swing about its pivot.

The inner end of the actuating lever E has a sliding connection with the guide lever D, consisting, as shown, of the reduced inner end f of the part e'' of the actuating lever E projecting into a loop or eye f' formed on the end of the guide lever D and projecting downwardly therefrom. By means of this connection the depressing of the outer end of the lever causes the knuckle to be raised to its lock releasing position, as shown in Fig. 2, and the parts are again returned to their normal position by gravity.

The advantage of this construction over devices of this kind heretofore used lies

in the fact that all of the parts of the lock operating mechanism are arranged to move in substantially parallel planes which reduces the friction in the parts and prevents any of the parts from binding or becoming jammed. The lock operating mechanism is, therefore, easily operated and there is less wear on the parts thereof. The arrangement of the parts to move in parallel planes also prevents any twisting of the bearing pins connecting the links when the coupler swings sidewise due to the passing of the car around a curve, and thus avoids the possibility of breaking or injuring these parts of the mechanism. A coupler provided with the lock lifting rod or link C and lever D can be quickly applied to a car in operative connection with an actuating lever F already in place thereon, since it is only necessary to insert the reduced inner end of the lever

F into the eye f' of the lever D on the coupler.

I claim as my invention:

The combination with a car coupler having a knuckle lock, of a rod passing through an opening in the bottom of the coupler for actuating said lock, a guide lever pivoted on the coupler head to swing in a vertical plane extending transversely of the coupler and operatively connected to said rod, and an actuating lever pivoted on the car to swing in a vertical plane transversely thereof and operatively connected with said guide lever and rod.

Witness my hand, this 4 day of September, 1913.

WILLARD F. RICHARDS.
